UNITED STATES PATENT OFFICE.

EDGAR KIDWELL, OF MILWAUKEE, WISCONSIN, ASSIGNOR TO KIDWELL BOILER COMPANY, OF MILWAUKEE, WISCONSIN, A CORPORATION OF WISCONSIN.

BOILER CONSTRUCTION.

Application filed October 12, 1920. Serial No. 416,393.

To all whom it may concern:

Be it known that I, EDGAR KIDWELL, a citizen of the United States, and resident of Milwaukee, in the county of Milwaukee and State of Wisconsin, have invented certain new and useful Improvements in Boiler Constructions, of which the following is a specification.

This invention relates to boilers of the series drum and tube type wherein the water circulating path is constituted by a series of transverse drums and connecting water tubes, one or more of said drums having its or their heads yieldingly positioned within an opening in the wall of the setting in such a manner as to permit limited bodily movement of the drum or drums in order to compensate for the variable expansion of the tubes. Such movement may be as great as $\frac{1}{8}$ of an inch, and therefore there must be a corresponding clear space left between the boiler head rivets and the adjacent housing wall. It has heretofore been the practice to pack the space with asbestos rope in order to prevent the leakage of air into the setting, but owing to the bodily working of the drum the packing material is crushed to one side and released. The resulting leakage of air materially impairs the efficient operation of the boiler, for the reason that such air seriously reduces the draft and minimizes the percentage of CO_2 in the gaseous products of combustion, thus causing a serious fuel waste.

The object of my invention is to remedy the objection mentioned, and to that end I provide a novel construction and organization of parts whereby a reliable joint or connection is established between a drum and the setting of the boiler as will be hereinafter described and claimed.

In the drawings—

Figure 1 is a transverse section, partly in plan, of a portion of the wall of a boiler setting with one end of a drum positioned therein, showing my improved joint construction.

Fig. 2 is a front view, partly in section, of the structure shown in Fig. 1.

Figs. 3 and 4 are perspective views of single bricks which are used in constructing the packing supporting rings of the setting.

Referring to the drawings, 5 designates

one end of a suspended boiler drum, and 6 a portion of the setting wall having a circular opening within which such end, including the riveted drum head 7, is loosely entered and is therein surrounded by packing. In pursuit of my invention in its preferred form I construct this opening by means of inner and outer rings of bricks 8, 9, respectively, which are specially shaped and so relatively arranged as to ensure the locking of the packing in place and thus prevent its dislodgement by the movement of the drum due to the expansion of the water tubes. The inner ring of bricks 8 is of greater diameter than the boiler drum, so as to afford the requisite clearance for the latter. Each of the bricks 8 is formed in its inner face with a groove, 10, of such character that when the ring is constructed it presents an annular groove in close relation to the circular series of rivet heads 11. This groove enables the bricks 8 to be placed with a minimum clearance, about $\frac{1}{4}$ of an inch, between them and the adjacent rivet heads. A ring 12 of asbestos rope packing is placed between the rivet heads and the outer edge of the groove in the ring of bricks 8 so as to fill the intervening space, and in front of this rope is well packed dry fibrous asbestos 13. This being done the outer ring of bricks 9 is installed, the same being of less internal diameter than the inner ring of bricks 8 as shown. The bricks 9 are tapered on their inner ends, as at 14, to present an inclined surface 90 spaced from the opposing face of the drum head. The clearance thus afforded between the inclined surface 14 and the drum head is preferably about $\frac{1}{8}$ of an inch. When the ring of bricks 9 has been installed, more dry asbestos is packed in, and then two rings of asbestos rope, as 15, are applied to the space between the ring of bricks 9 and the boiler head and therein tightly caulked.

By the construction just described the drum has capacity for ample backward and forward movement at right angles to the longitudinal axis of the drum and, by means of the groove in the bricks 8 in conjunction with the described disposition of the asbestos ropes, the packing is most effectually locked in place and a tight and reliable joint is ensured; that is to say, the rivet heads lock the rope 12 firmly against the opposing portion of the groove and such rope thus

acts as a continuous seal to prevent the packing 13 from shifting into the spaces between and surrounding the rivet heads. The outer ropes are caulked in place to prevent the packing 13 falling outward.

Without limiting myself to the precise details of construction disclosed, what I claim is—

1. A boiler having a setting with an opening in the wall thereof, and a drum having its head and a portion of its cylindrical shell loosely entered in the opening, said opening being formed by a ring structure built into the setting and presenting two internal face portions whereof one encircles the shell and is in spaced relation thereto and has an annular groove in proximity to the drum head rivets, and whereof the other face portion is inclined and in spaced relation to the drum head, and packing material disposed between the ring structure and the adjacent portions of the drum head and shell, so as to bear against the opposing rivet heads and be restrained thereby.
2. In a boiler having a setting with an opening in the wall thereof, and a drum having its head loosely entered in said opening, inner and outer rings built into the setting to constitute the opening to receive the head of the drum, the inner ring being of greater diameter than the drum and having an internal groove in proximity to the drum head, and the outer ring being of less internal diameter than the inner ring and having an inclined surface in spaced relation to the outer face of the drum head, and packing material disposed between the rivet heads and the outer edge of the groove, loose fibrous material packed between the two rings and the proximate portions of the drum, and a rope or ropes packed between the outer ring and the face of the drum head.

rivets of the drum head, and the outer ring being of less internal diameter than the inner ring and having an inclined surface in spaced relation to the outer face of the drum head, and packing material disposed between the rivet heads and the outer portion of the groove and also in the space between the boiler head and the two rings.

3. In a boiler having a setting with an opening in the wall thereof, and a drum having its head loosely entered in said opening, inner and outer rings of bricks built into the wall of the setting to constitute the opening to receive the head of the drum, the inner ring being of greater diameter than the drum and having an internal groove in proximity to the drum head, and the outer ring being of less internal diameter than the inner ring and having an inclined surface in spaced relation to the outer face of the drum head, a packing rope disposed between the rivet heads and the outer edge of the groove, loose fibrous material packed between the two rings and the proximate portions of the drum, and a rope or ropes packed between the outer ring and the face of the drum head.

Signed at Milwaukee, in the county of Milwaukee and State of Wisconsin, this 8th day of October A. D. 1920.

EDGAR KIDWELL.
